UNITED STATES PATENT OFFICE.

WILLIAM M. HURLEY, OF BROCKTON, MASSACHUSETTS.

SHOE AND ARCH SUPPORT THEREFOR.

Application filed December 15, 1926. Serial No. 155,035.

This invention relates to shoes and has for an object the provision of a support for the metatarsal bones of the foot, which is, in itself, a complete and inexpensive article of manufacture and is adapted to be sold as such, and which is so arranged that it can be applied readily to a shoe by a shoe repairer without the exercise of any material degree of skill, although provision may be made in the shoe, in the process of manufacture thereof, for the arch support, when desirable.

A further object is the provision of a metatarsal arch support which has a resilient detachable connection with the shoe.

Another object is a method of attaching the arch-support to the shoe.

A yet further object is generally to improve the construction of shoes.

Fig. 1 is a side elevation, partly broken away, of a shoe embodying the invention.

Fig. 2 is a plan view of the support.

Fig. 3 is a reverse view of Fig. 2.

Fig. 4 is a perspective section taken along line 4—4 of Fig. 2.

Fig. 5 is a fragmentary plan view of an inner sole and especially illustrating the slits therein which are adapted to receive the arch support.

As here shown, the metatarsal arch support embodying the invention includes a more or less flexible member or pad 10, preferably of leather, which is of substantial length as compared to its width, and is widest at the forward end 12 and is tapered toward the rear end. Said member is flat on its bottom face 14 and is of varying thickness. The forward end is the thickest and is more or less dome-shaped with the apex 16 thereof in the middle of the dome and the thickness diminishes toward the edge of the member; and the edge is relatively thin. The body-portion of the member, in the rear of the dome, is relatively, and preferably uniformly, thin along the longitudinal axis thereof and tapers to a thin edge at the sides. The dome of the pad is adapted to lie under and support the metatarsal bones of the foot while the body portion is adapted to lie under the instep.

The pad is carried by, and overlies on all sides of a relatively narrow supporting plate 18 which preferably is of some thin springy metal as tempered steel. The pad and plate are secured together by suitable means as rivets 20. Said plate is adapted to be supported at the ends thereof and preferably is bowed

upwardly in the middle to provide a somewhat yielding support for the longitudinal arch of the foot. The ends 22 and 24 of said plate are of reduced width, as best illustrated in Fig. 3, and are reflexed downwardly below the body of the plate to form lips by which the support is attached to the shoe.

The support, as thus described, is adapted to be sold as a complete article of manufacture, to be inserted in a shoe by the purchaser or by a shoe repairer.

In installing the support in a shoe, a pair of slits 26 and 28 respectively are cut in the inner sole 30 in or adjacent to the shank portion and in the line of the longitudinal axis of the sole. Any suitable or convenient form of tool, as a chisel, may be used for this purpose. The slits may extend entirely through the inner sole and need not extend into the outer sole 32. The slits are inclined diagonally downward in opposite directions, the slit 26 being inclined downward toward the heel and the slit 28 toward the fore part of the shoe. The lips 22 and 24 of the plate 18 of the arch support are adapted to be inserted in the slits as illustrated in Fig. 1, the plate 18 being temporarily flexed for this purpose, and the resiliency of the plate serves to hold the lips removably in the slits without the necessity for other attaching means. The location of the slits is such that when the support is in place in the shoe, the dome 16 is disposed beneath and in position to support the metatarsal bones of the foot. The support is in contact with the inner sole mainly at the ends thereof, with the middle of the support arched above the ends, and thus provides a yielding support for the longitudinal arch of the foot; and the slits provide abutments which limit the extension of the plate 18 due to the flattening thereof.

I claim:

1. As a new article of manufacture, an arch support for shoes comprising a relatively long and generally narrow pad adapted to overlie the inner sole of a shoe at the shank portion thereof and to extend along the line of the longitudinal axis thereof, and having its greatest thickness in the forward portion thereof, and having means at the ends thereof for detachably securing the support to the inner sole.

2. As a new article of manufacture, an arch support for shoes comprising a relatively long and generally narrow pad adapted to overlie the inner sole of a shoe at the shank portion

thereof and to extend along the line of the longitudinal axis thereof, and having its greatest thickness in the forward portion thereof, and a relatively narrow spring strip attached to the under face of the pad, in the line of the longitudinal axis thereof, and having at its ends means for detachably securing the support to the inner sole.

3. As a new article of manufacture, an arch support for shoes comprising a relatively long and generally narrow pad adapted to overlie the inner sole of a shoe at the shank portion thereof and to extend along the line of the longitudinal axis thereof, and having its greatest thickness in the forward portion thereof, and a relatively narrow spring strip attached to the under face of the pad, in the line of the longitudinal axis thereof, said strip having its ends reflexed below the general body thereof to provide attaching lips adapted detachably to secure the support to the inner sole.

4. A shoe having an arch support including a relatively long and narrow pad overlying the shank portion of the inner sole of the shoe along the longitudinal axis thereof and having means at its ends detachably connecting it with the inner sole.

5. A shoe having an arch support including a relatively long and narrow pad overlying the shank portion of the inner sole of the shoe along the longitudinal axis thereof, a resilient

strip attached to the under face and extended lengthwise of the pad and having attaching lips at its ends, and said inner sole having slits therein in which said lips are removably received.

6. A shoe having an arch support including a relatively long and narrow pad overlying the shank portion of the inner sole of the shoe along the longitudinal axis thereof, said pad having attaching lips at its ends, and said inner sole having slits therein in which said lips are removably received.

7. A shoe having an arch support including a relatively long and narrow pad overlying the shank portion of the inner sole of the shoe along the longitudinal axis thereof, and attached to the inner sole at the ends only, said pad being elevated above the inner sole intermediate its ends.

8. A shoe having an arch support including a relatively long and narrow pad overlying the shank portion of the inner sole of the shoe and extended along the longitudinal axis thereof, a resilient strip attached to the under face and extended lengthwise of the pad and bearing on the inner sole only at its ends, said strip and pad being elevated above the inner sole intermediate its ends.

In testimony whereof, I have signed my name to this specification.

WILLIAM M. HURLEY.
